(57) **CLAIM**

The ornamental design for a hat with a ponytail hole, as shown and described.

DESCRIPTION

FIG. 1 is a front perspective view of a hat with a ponytail hole with a middle portion in an open position;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof;

FIG. 7 is a bottom plan view thereof; and,

FIG. 8 is a front perspective view thereof of the hat with a ponytail hole with the middle portion in a closed position. The broken lines shown in the figures depict portions of the hat with a ponytail hole that form no part of the claimed design.

1 Claim, 8 Drawing Sheets
